UNITED STATES PATENT OFFICE.

LUTHER WM. GAMBLE, OF NEVADA, MISSOURI.

DESIGN FOR A PENWORK-RECORD.

44,920.

Specification for Design.

Patented Nov. 25, 1913.

Application filed September 2, 1913. Serial No. 787,810. Term of patent 7 years.

To all whom it may concern:

Be it known that I, LUTHER WILLIAM GAMBLE, a citizen of the United States, residing at Nevada, in the county of Vernon and State of Missouri, have invented a new, original, and ornamental Design for Pen-work-Records, of which the following is a specification, reference being had to the accompanying drawing, forming part thereof.

The figure is a plan view of a pen work record, showing my new design.

I claim:

The ornamental design for a pen work record, as shown.

LUTHER WM. GAMBLE.
